US00D690482S

(12) **United States Design Patent**
Bergman et al.

(10) **Patent No.:** **US D690,482 S**
(45) **Date of Patent:** **** Sep. 24, 2013**

(54) **PAINT APPLICATION CONTAINER**

(71) Applicant: **Bercom International, LLC**,
Chanhassen, MN (US)

(72) Inventors: **Christopher M. Bergman**, Hopkins,
MN (US); **Mark W. Bergman**,
Minnetonka, MN (US); **Jeffrey T.**
Given, St. Paul, MN (US); **Matthew V.**
Leyden, St. Paul, MN (US); **Jeffrey B.**
Waffensmith, North Oaks, MN (US)

(73) Assignee: **Bercom International, LLC**,
Chanhassen, MN (US)

(**) Term: **14 Years**

(21) Appl. No.: **29/445,954**

(22) Filed: **Feb. 19, 2013**

Related U.S. Application Data

(62) Division of application No. 29/409,474, filed on Dec.
23, 2011, now Pat. No. Des. 678,638.

(51) **LOC (9) Cl.** **07-07**

(52) **U.S. Cl.**

USPC **D32/54**

(58) **Field of Classification Search**

USPC D32/53-54; 220/495.01, 495.02,
220/570, 904; 15/260-264

OTHER PUBLICATIONS

Painters' Helpers Sporty's Tool Shop (1 page) bearing copyright notice of 2001.

Fourteen (14) pages of photos of a pail known to the public prior to Apr. 29, 2004.

Primary Examiner — Robin V Webster

(74) *Attorney, Agent, or Firm* — James L. Young; Westman, Champlin & Kelly, P.A.

(57) **CLAIM**

The ornamental design for a paint application container, as shown and described.

DESCRIPTION

FIG. 1 is of a perspective view of a paint application container showing our design;

FIG. 2 is an end view thereof, as taken from the right end of FIG. 1;

FIG. 3 is an end view thereof, as taken from the left end of FIG. 1;

FIG. 4 is a right side view thereof;

FIG. 5 is a left side view thereof (the side views are mirror images of one another);

FIG. 6 is a top view thereof; and,

FIG. 7 is a bottom view thereof.

The broken lines in the FIGS. 1-7 are for illustrative purposes only and form no part of the claimed design in those embodiments.

1 Claim, 5 Drawing Sheets
